STENCIL FOR AND PROCESS OF PRINTING

Paul Joseph Csaszar, New York, N. Y.

Application November 3, 1938, Serial No. 238,548

1 Claim. (Cl. 101—129)

This invention relates to stencil sheets and to processes for making multicolored designs by means of stencils.

In the production of multicolored posters and designs, by means of stencils, the usual procedure is to outline the parts which are to be colored on a sheet of stencil material and remove from the stencil material the area outlined. When a plurality of colors are to be used, a stencil is formed for each part of the design to which each color is to be applied. For example, if a design has a number of areas in which red is to be applied, a stencil is cut to remove those portions corresponding to the red parts of the design. Similar stencils are similarly formed for the remaining colors. The various stencils are affixed to tautly stretched pieces of fine meshed fabric, such as silk, and the color is applied through the uncovered portion of the silk onto the surface that is to bear the design. The stencils are used successively to apply the various colors so that when all of the stencils have been used and the colors applied, a complete design in colors is formed. Preparation of the stencils requires considerable skill and many operations in order to produce reasonably faithful reproduction of the coloration of the desired design. However, even with the most careful work and the use of a great many stencils, it is almost impossible to produce accurate shading and true rendition of the tonal values of the design.

Shading or gradual change in color values ordinarily are obtained by applying the colors in the desired areas with an air brush. However, air brush work is somewhat unsatisfactory except when done by a highly skilled artisan, for the reason that it is extremely difficult to apply paint uniformly to a series of designs and even then is very slow.

It is well known, of course, that colors can be readily reproduced with printing plates prepared photographically by means of half-tone screens. Half-tone plates, or other photographically prepared plates, however, are considerably more expensive than stencils and many operations as well as a high degree of skill are required in their preparation, thereby rendering their use economically unsatisfactory for the production of small numbers of colored designs. It would be highly desirable, therefore, to produce a process and materials which are substantially as inexpensive in use as stencils and at the same time capable of reproducing color values as faithfully

as half-tone or other photographically prepared plates.

An object of the present invention, accordingly, is to provide stencil materials capable of producing half-tone effects.

Another object of the invention is to provide stencil sheets for producing shaded sections or sections having gradually changing color values in a multicolored design.

10 An additional object is to provide stencil sheets which are perforated so that colors applied through the perforations will print as dots, thereby allowing control of shade and tint of printed color by variations in the size and spacing of the dots.

20 Another object of the invention is to provide a method of using perforated stencils to produce multicolor effects, blend colors, and to vary intensity, shade and tone of the colors in the production of multicolor designs.

25 Stencils embodying the invention consist generally of thin material, preferably transparent or translucent, having a multiplicity of minute perforations therein. The size of the perforations may be varied, as desired, but are on the order of the size of dots produced by means of a fairly coarse half-tone screen or larger. Preferably the size of the perforations in one stencil sheet is the same and a plurality of sheets each having perforations of different size form a complete set of stencils. However, in some instances it may be desirable to provide stencil sheets in which the pattern and the size of the perforations will vary in order to produce smoothly 30 graduated variations in the tone or density of the color applied therethrough.

35 The material from which the stencil sheets are formed may vary widely. For example, cellulose films or lacquers, paper, metallic foils, films formed from synthetic or natural resins, fabrics having glue or lacquer or gelatin coatings or other similar tough material which prevents penetration or passage of color may be used. Inasmuch as the coloring materials may be paints, inks, lacquers, varnishes, powders or crayons, a great variety of materials may be used as stencil materials depending largely upon the type of coloring materials to be used therewith. If desired, the stencil sheets may be laminated, having a paper base and a detachable film thereon, which is capable of being cut into the desired shape and applied to the fabric screen. An example of this type of material is disclosed in the U. S. patent to D'Autremont, No. 1,781,834, dated November 18, 1930. Such materials may be used

with great facility for the reason that they allow the stencil to be cut accurately and are readily applied to the fabric screen without distortion.

In its broadest aspects the process consists generally of the steps of forming stencils by removing portions which encompass the area in which a single solid color is to be placed and producing shades or tones of this color or blends of the color with an adjacent color by means of perforations in the stencil. The stencil preferably is affixed to a fabric screen, and the color may be applied through the open portions to the material which is to bear the design. Gradation in intensity and tone and blending of colors can be controlled by the use of perforated stencil portions which include perforations of varying size. The colors may be blended by superimposing colors through overlapping portions of successive stencils and thus not only may a great variety of shades and tints be produced but the number of colors required to produce the design may be materially reduced.

For a better understanding of the present invention, reference may be had to the accompanying drawing, in which

Figure 1 is a plan view of a design to be reproduced by means of stencils;

Fig. 2 is a plan view of a stencil for applying the yellow portions of the design;

Fig. 3 is a stencil for applying the red portions of the design;

Fig. 4 is a stencil for applying the blue portions of the design; and

Figs. 5 to 11 are plan views of sections of modified forms of stencil sheets with the perforations therein shown greatly enlarged.

Illustrative of one form of the stencilling process and the stencils used therein, the invention will be described with reference to the production of the design 10 shown in Fig. 1. The design 10 includes a yellow lighthouse 11 on a dark green strip of land 12, a light blue sky 13, a dark blue sea 14 and a red buoy 15 having a purple shaded portion 16. In accordance with applicant's process the design may be reproduced by means of three stencils 17, 18 and 19, shown respectively in Figs. 2, 3 and 4. The stencil 17 is formed by superimposing on the design 10 a sheet of stencil material 20 and outlining thereon the portions which are to be reproduced in yellow and green. In this instance the lighthouse 11 and the strip of land 12 will be outlined and the area within the outlines removed. The stencil material is then applied to a strip of fine mesh material 21, such as for example silk, or of wire mesh fabric which is stretched tightly in a frame 22. If this stencil were used directly the strip of land 12 and the lighthouse 11 would be reproduced as a uniform yellow color. However, the strip of land 12 is to be a natural or dark bluish green color and accordingly a strip of perforated stencil material 23, such as any of those shown in Figs. 5 to 11 is inset into this cutaway portion.

The stencil sheet disclosed, for example, in Fig. 5, consists of a sheet 23 of pliable thin material having a plurality of very small perforations 24 therein. The perforations 24 may be circular and may be of a size corresponding to the dots produced by a coarse half-tone screen or they may be larger, for the reason that in stencil work the screen pattern need not be particularly subdued. The size of the dots 24 may be varied on different sheets, for example as shown in Fig. 6, the perforations 24 may be considerably larger

than the perforations 24 and more closely spaced in order to produce a deeper or more intense tone when the paint is applied therethrough. Likewise, as shown in Figs. 7 and 10, the perforations 26 and 27, respectively, may be oval in shape and arranged either in lines or in the form of interlocking clover leaves. Many modifications of the pattern and shape of the perforations are possible, in addition to those described above. For example, as shown in Fig. 8, the perforations 28 may be substantially rectangular in shape and, as shown in Fig. 9, the perforations 29 may be arranged in sinuous and transversely extending straight rows.

As shown in Fig. 11, it is possible likewise to produce uniform gradations of tone by varying the size of the perforations from the small perforations 30, to larger and more closely spaced perforations 31. This form of stencil sheet and likewise those disclosed in Figs. 5 to 10 may be of laminated construction consisting of a thin film 31a of, for example, lacquer shellac or cellulose material which is supported on but separable from a paper base 31b. The film 31a may have glue or other adhesive on its face to facilitate its application to a fabric screen. The perforations 30, 31 may be formed in the film 31a or through the film 31a and base 31b.

It will be apparent that by varying the size and the spacing of the perforations, the amount of paint or ink that can pass through the stencil will likewise be varied and thus will vary the shade or intensity of the color.

In determining the type of perforated stencil that is to be applied for reproducing the green in land 12 of the design, due care must be used in the selection of stencil portions having the appropriate size perforations. When this has been determined the perforated stencil material may be placed in the proper position and color applied as by means of a squeegee roll through the open part of the stencil. A similar result may be obtained by using a perforated stencil sheet for the entire stencil, cutting away a portion corresponding in shape to the lighthouse and coating all except the land part thereof with a material such as lacquer or varnish to fill up the perforations, thus permitting coloring material to be applied through the lighthouse and land portions of the stencil only.

The red stencil 18 is prepared in a similar way. That is, only the portion corresponding to the buoy including the red portion 15 and the purple portion 16 are cut from the stencil and this stencil is likewise applied to a fabric screen 21, superimposed on the yellow printed portion of the design and red coloring material applied through the opening in the stencil 18.

The blue stencil 19 is formed by applying to the fabric screen 21 portions of imperforate stencil material 20 for preventing application of blue to the yellow printed portion of the lighthouse 11 and the red portion of the buoy 15. Inasmuch as the lower portion of the design 14 is to be printed a dark blue, no stencil material is applied to the lower portion of the screen 21. The upper portion of the design corresponding to the sky 13 is to be printed a lighter blue and therefore a portion of perforated stencil 22 of a type similar to any of those disclosed in Figs. 5 to 10 is applied to the upper portion of the screen. If it is desired to shade the blue portions it will be understood that a plurality of strips of stencil material having different sizes of apertures therein may be used or a portion of stencil

material having graduated perforations therein, such as is disclosed in Fig. 11, may be used.

Likewise, a portion of the perforated stencil 33 may be applied to the screen 21 corresponding to the part of the buoy which is to have a purple coloration in order to hold back the blue and cause the portion 16 of the final design to have a reddish, purple cast. The completed stencil 19 is then superimposed upon the yellow and red printed portion of the design in register therewith and blue applied through the stencil. The combination of the blue with the yellow in the part 12 of the design will produce a green coloration of the portion 12, the lighthouse will be yellow, the left-hand portion 15 of the buoy will be red and the combination of red and blue in the portion 16 of the buoy will produce a purplish color. Likewise, the sea portion 14 will be dark blue, while the perforated stencil 32 will cause the sky portion 13 to print a lighter blue, thereby reproducing faithfully the colors that are desired in the design. To produce black, the colors may be superimposed by cutting out registering portions of the stencils as at 34 in Figs. 2, 3 and 4.

The use of perforated stencils of the type described above greatly reduces the number of operations and stencils that are required to produce a desired design. The reason for this is that the perforated stencils more or less automatically control the shade or intensity of the colors and likewise permit the colors to be blended to produce intermediate color values. Thus with three stencils and three colors it is possible to produce many shades of color in addition to all colors produced by combination of the three colors used. The perforated stencils do not appreciably alter the procedural or mechanical steps of printing and therefore may be used

with facility by those who are familiar with prior stenciling practice.

It will be understood that the stencil sheets in themselves are susceptible to wide variations in the size and shape of perforations as well as the type of materials from which they are made. Substantially any material may be used, but preferably translucent or transparent materials such as celluloid, Bakelite, shellacked or lacquered papers or fabrics, glued papers, or cellulose or cellulosic derivatives are used in order to facilitate the outlining of the sections that are to be removed from the stencils. If the stencils have sufficient strength, they may be used without a supporting screen. Therefore it will be apparent that many changes may be made in the specific details of the stencil sheets and their uses extended to fields other than that described above, without departing from the invention. Therefore it should be understood that the embodiments described above should be considered as illustrative and not as limiting the scope of the following claim.

I claim:

25 The process of making designs having solid and shaded tones, comprising forming a stencil with cut-out portions encompassing the solid and shaded tones of the color to be reproduced, fixing the stencil to a sheet of fine mesh fabric, fixing 30 to the fabric in the areas corresponding to the shaded tones stencil material having a multiplicity of perforations therein that vary in size in proportion to the density of the tone to be reproduced, and applying color to a sheet through the stencil and fabric to produce said 35 solid and shaded tones.

PAUL JOSEPH CSASZAR.
